UNITED STATES PATENT OFFICE.

ALPHONSO S. COMSTOCK, OF EVANSTON, ILLINOIS.

DESIGN FOR A TWINE-HOLDER.

SPECIFICATION forming part of Design No. 25,705, dated June 30, 1896.

Application filed May 23, 1896. Serial No. 592,886. Term of patent 14 years.

To all whom it may concern:

Be it known that I, ALPHONSO S. COMSTOCK, a citizen of the United States, residing at Evanston, in the county of Cook and State of Illinois, have invented and produced a new and original Design for Twine-Holders, of which the following is a specification, reference being had to the accompanying drawings, which are made a part hereof, and in

10 which—

Figure 1 is a perspective view of a twine-holder embodying the design. Figs. 2 and 3 are elevations thereof viewed from different positions.

15 The present invention resides in a twine-holder comprising two arms or branches A A', which taken together and viewed edgewise present an outline resembling in shape the letter L. Preferably the junction between 20 the two arms is rounded somewhat, as shown at a, in order to avoid the formation of a sharp angle. In one of the branches, A, near its end, is a circular opening B. In the other branch, A', near its junction with the branch

A, is a circular opening C, and at its outer end it is provided with a notch D, resulting in two tongues a' a'. Preferably the end of the branch A and also the ends of the tongues a' a' are rounded.

One of the essential features of the design 30 is the approximately L shape of the holder, without regard to its form at the junction of the two branches. Another essential feature of the design is the configuration which is given to the branch A' by reason of the notch 35 D and opening C, without regard to the shape of the opening or the outline of the tongues resulting from the notch.

In its entirety the design embraces all of the features above described. 40

What I claim as new, and desire to secure by Letters Patent, is—

The design for twine-holders, substantially as herein shown and described.

ALPHONSO S. COMSTOCK.
